UNITED STATES PATENT OFFICE

ALFONSO FLORES MIRAFUENTES, OF GUADALUPE, MEXICO

HAIR CUTTING SCISSORS

Application filed June 5, 1930. Serial No. 459,269.

This invention relates to a tonsorial device, and more particularly it relates to a hair cutting scissors which is adapted to be satisfactorily and easily manipulated by a person to cut his own hair.

Cutting one's hair is beset with difficulties. Clippers and trimmers of various sorts have been placed on the market and while they may be used for trimming the hair around the ears and back of the neck, there has never been produced a scissors which may be used successfully for trimming as well as for removing hair from the top of the head and which may be used by one to cut his own hair. The usual barber's scissors is not applicable for this purpose. An even cut cannot be obtained without the use of a comb, and even then it is well nigh impossible with such implements for one to cut hair at the back of his head. Even when the cutting operation is performed by another, great skill is required in giving a neat hair cut.

If only a barber's scissors is used, it will be found that the hair has a tendency to bunch between the blades and to slide toward their extremities thus escaping from being cut. If the blades do cut some of the hair, the result will be jagged and unsightly. It has also been found that the usual scissors, being pivoted at the point of crossing, do not effect an even tension the entire length of the cutting edge but only in close proximity to the point of pivoting. This disadvantage in itself virtually prevents the giving of a neat hair cut to one's self with a barber's scissors.

The invention set forth in this specification has manifold advantages. As it permits the operator to cut his own hair neatly, and without requiring previous experience, it is a great blessing in the rural districts where barbers are scarce or not available at all. Also in the cities and towns where hair cuts are expensive, the device will prove a great benefit to the thrifty individual or family.

One object of this invention is to provide a device for cutting hair and which may be used by the operator for cutting his own

hair without requiring previous experience.

Another object of this invention is to provide a device of the type described which will insure an even, neat hair cut.

The invention further contemplates as an object the provision of a hair cutting scissors in which the tension of the blades is even throughout the entire length of the cutting edges of the blades, and which will prevent the hair from bunching and sliding between the blades.

Further objects and advantages will become more apparent from the specification and the appended claims read in connection with the accompanying drawings.

In the figures:

Fig. 1 is a side view of the scissors;

Fig. 2 is a front view; and

Fig. 3 illustrates the manner of manipulating the scissors.

The device as illustrated in the drawings is comprised of two crossed blade members 2 and 4. These blade members are provided with opposed cutting edges 6. The blades are pivotally connected at the point of crossing by a bolt 8 passing through apertures in the blades, and a nut 10 is used to secure the blades together on the bolt. Handles 12 are provided at one end of the blade members. The handles may be grasped to manipulate the device in the manner of the usual scissors.

On the outer side face of the blade 2 is a comb member 14 having teeth 16 projecting inwardly past the cutting edge of the blade. The comb member is flush with the outer side face of the blade and is secured thereto by means of threaded screws 18 and 20 which pass through apertures in the comb member and are engaged by threaded apertures in the blade member. The screw 20 does not pass through the aperture so as to protrude from the blade. The other screw 18, however, does protrude from the inner surface of the blade so as to act as a stop member as will hereinafter be described.

A handle 22 is threadedly engaged by an aperture in the blade member 2 and near the end thereof. The handle projects from the inner flat surface of the blade member

and at right angles thereto. When in operation, this handle is hooked or grasped by the thumb or fingers while the scissors is used. The handle is a most important feature of the invention because it makes possible an even hair cut at the back of the head.

One of the most pertinent disadvantages encountered in using the regular barber's scissors for cutting one's hair is that the tension of the blades is not even the entire length of the cutting edge. To cut hair evenly between the blades near the ends thereof is not usually possible for there is not sufficient pressure exerted at this point to provide tension to keep the blades together during cutting.

In the present invention this great objection is obviated by the use of a plate spring 24, which is normally arced as illustrated by the dotted lines in Fig. 1. In use the spring extends along the outer surface of the blade member 4, and is secured thereto by the bolt 8. This plate spring extends substantially to the end of the blade member, and a small recess 26 in the blade member is provided for engaging a small projection 28 on the inner face of the spring to retain the spring in position.

The scissors described above is easily operated by grasping the handles 12 with one hand and the handle 22 with the other so as to properly guide the device when cutting one's hair, and particularly when cutting hair at the back of the head and neck. The screw 18, as previously mentioned, protrudes through the blade and acts as a stop to prevent the other blade from cutting the fingers of the operator while holding the handle 22.

It is also apparent that the scissors may be used for cutting another's hair in which case the handle 22 is an aid but may be dispensed with if not desired. So may the scissors be used for cutting materials. The comb member 14 and the handle 22 may then be removed or may be left on the scissors to suit the whim of the user.

The device as described is not only simple in structure and operation, but may be inexpensively manufactured to sell at a price within the reach of all.

Having now described my invention, what I claim as new and desire to secure by Letters Patent of the United States is:

1. A scissors comprising crossed blades pivotally connected, handles at one end of the blades for grasping the scissors, a removable comb secured to the outer surface of one of the blades, the teeth of said comb extending beyond the cutting edge of the blade, and a removable knob handle projecting from the inner face of said blade and near the end thereof, said handle projecting substantially at right angles to said inner face of the blade.

2. A hair cutting scissors adapted to be manipulated by the person whose hair is to be cut, crossed blades pivotally secured, a comb removably secured to the outer side face of one of said blades, the teeth of said comb extending beyond the cutting edge of the blade, a removable knob handle secured to the opposite side of said comb supporting blade and near the end thereof, said handle projecting substantially at right angles to the blade, a plate spring pivotally secured to the outer side face of the other blade at the point of crossing and extending along the blade substantially to the end thereof, and means for removably retaining the end of the spring in position on the blade, whereby the blades are forced together tightly to insure an even tension throughout the entire length of the cutting edges of the blades.

3. A hair cutting scissors adapted to be manipulated by the person whose hair is to be cut, crossed blades pivotally secured, a comb member removably secured by screws to the outer side face of one of said blades, the teeth of said comb extending beyond the cutting edge of the blade, and a removable knob handle secured to the opposite side face of said comb supporting member near the end thereof, said handle projecting substantially at right angles to the last named side face of the blade, one of the screws for securing the comb member to the blade extending through said blade and projecting therefrom to act as a stop to prevent the other blade from striking the knob handle.

In testimony whereof I have hereunto set my signature.

ALFONSO FLORES MIRAFUENTES.
